UNITED STATES PATENT OFFICE.

ROSS M. G. PHILLIPS, OF WEST HAVEN, CONNECTICUT, ASSIGNOR TO THE SENTINEL AUTOMATIC GAS APPLIANCE CO., OF NEW HAVEN, CONNECTICUT, A CORPORATION.

TIMING MECHANISM.

1,179,863.

Specification of Letters Patent.

Patented Apr. 18, 1916.

Application filed August 1, 1913. Serial No. 782,445.

To all whom it may concern:

Be it known that I, Ross M. G. Phillips, a citizen of the United States, residing at West Haven, in the county of New Haven 5 and State of Connecticut, have invented a new and useful Improvement in Timing Mechanism; and I do hereby declare the following, when taken in connection with the accompanying drawings and the characters of reference marked thereon, to be a full, clear, and exact description of the same, and which said drawings constitute part of this application, and represent, in—

Figure 1 a broken view in elevation, 15 showing my improved timing mechanism applied to a gas-heater connected with a boiler. Fig. 2 a detached view in front elevation of the timing-mechanism with a portion of its case broken away and its parts 20 being shown in their normal or inactive positions. Fig. 3 a corresponding view showing its automatic gas-valve in vertical section and its timing-dial released preparatory to setting the mechanism in operation. 25 Fig. 4 a corresponding view with its setting-lever swinging into its set-position. Fig. 5 a view of the timing-mechanism in rear elevation with the back of its case and the rear movement-plate of its time-train 30 removed. Fig. 6 an edge view of the device with its case in vertical section and its supply-mechanism in elevation with the exception of its supply-limiting lever which is shown in section. Fig. 7 a view of the device in horizontal section on the line *a*—*b* of Fig. 6 and looking downward. Fig. 8 a 35 detached broken view in inside elevation of the frame-plate of the device showing also the timing-disk, the supply-limiting lever and the operating-link. Fig. 9 a view in 40 front elevation of one of the modified forms which my invention may assume, the lower portion of the case being broken away.

My invention relates to an improvement 45 in timing-mechanism for use in turning off gas used as an illuminant or as fuel, for shutting off or turning on an electric current, and so on, the object being to produce a simple, reliable and convenient device 50 having a wide range of use.

With these ends in view my invention consists in a timing-mechanism having certain details of construction and combinations of parts as will be hereinafter described and pointed out in the claims.

For the purpose of illustrating my invention, I have shown it as attached to an ordinary gas-heater 2 respectively connected at its upper and lower ends by pipes 3, 4, to a water boiler 5 mounted on a standard 6. 60 My improved mechanism, as shown, has a setting-lever 7 furnished at its lower end with a handle 8 and having its upper end formed with an indicator or pointer 9 which sweeps over the graduations of a dial 10 applied to the upper portion of the outer face of a sheet-metal case 11. The said lever 7 which is located in front of the said case, is rigidly secured by a screw 12 to the projecting forward end of a bearing-hub 13 journaled in the frame-plate 14, and formed integral with a concentric shoulder 15 located upon the outer face of a timing-disk or member 16 having a segmental timing-slot 17 receiving a timing-pin 18 carried by 75 a supply-limiting lever 19 located within the said case 11 close to the rear face of the frame-plate 14 which is fixed within the said case 11 at the extreme front thereof as shown in Fig. 6. 80

For driving the timing-disk or member 16, it is formed upon its inner face with a concentric driving-hub 20 (Fig. 8) having a square opening 21 receiving the squared forward end 22 of the main-spring arbor 23 85 the rear end of which has bearing in the rear movement-plate 24 which has a complementary front movement-plate 25, both of ordinary construction. A main spring 26 coiled upon the said arbor 23 has its inner 90 end fastened thereto and its outer end fastened to one of the movement-pillars in the usual manner. A winding-ratchet 27 mounted upon the rear end of the arbor 23, has its teeth cut so that each tooth shall represent a predetermined amount of time, say, 95 five minutes, as in the present construction. These teeth are engaged by a pawl or dog 28 operated by a spring 29 and swinging upon a pin 30 in the main-wheel 31 of the 100 time-train which may be of any convenient and approved construction. In the time-train shown in the accompanying drawings, the said main-wheel 31, which turns loosely upon the said arbor 23, meshes into a lantern-pinion 32 mounted upon an arbor 33 carrying a wheel 34 which meshes into a lantern-pinion 35 mounted upon an arbor 36 carrying a wheel 37 which meshes into a lantern-pinion 38 mounted upon an arbor 39 105 110

carrying a wheel 40 which meshes into a lantern-pinion 41 mounted upon an arbor 42 furnished with an escapement-wheel 43 the teeth of which co-act with a verge or 5 pallet 44 mounted upon a verge-arbor 45. The said verge 44 has a depending wire 46, the oscillation of which, and hence the speed of the train, is controlled in extent by 10 spring-fingers 47 regulated in the amount of their separation by means of a slender regulating-cone 48 formed upon the lower end of a rod-regulator 49 slotted at its upper end as at 50 for the reception of a screw-driver. The rod-regulator 49 is formed 15 near its lower end with threads 51 and passes through a threaded bearing 52 carried by a narrow plate 53 secured to the lower end of the rear movement-plate 24 and having the spring-fingers 47 attached to its lower end.

20 When the timing-disk 16 is being rotated by the time-train, the timing-pin 18 is held against the edge of the said disk, by means of a helical supply-limiting spring 54 having its lower end attached to the supply-limiting lever 19 and its upper end to the frame-plate 14 (Fig. 5), whereby the said spring exerts a constant upward pull upon the said lever which is lifted with a quick 25 upward movement when the said slot is brought into registration with the said pin which permits the lever to be lifted until the said pin reaches the upper end of the said slot.

For the manual operation of the supply-limiting lever 19 against the tension of its spring 54, its curved outer end is furnished with a stem 55 projecting forward through a segmental slot 56 in the frame-plate 14 and through a corresponding slot 57 in the case 40 11, the outer end of the stem carrying an operating-handle or knob 58 which, as it is pulled downward also moves from left to right in accordance with the circle in which it swings.

45 Preparatory to winding the main spring 26 by means of the setting-lever 7, the said knob 55 is pulled downward against the tension of the spring 54, whereby the pin 18 is drawn out of the slot 17 in the timing-disk 50 16.

The movement of the knob 58 downward and from left to right being continued, the stem 55 engages with the adjacent edge of the setting-lever 7, whereby the same is 55 swung from left to right for a sufficient distance to cause the open lower end of the slot 17 to move out of registration with the path of the pin 18. This initial movement of the lever 7 is effected solely by the stem 55 and knob 58 of the lever 19. Further movement 60 of the knob 58 and stem 55 downward, and also from left to right, finally causes the stem 55 to ride into a coupling-notch 59 in the adjacent edge of the setting-lever 7, whereby the setting-lever 7 and the supply-limiting lever 19 are temporarily coupled to-

gether. The handle 8 of the setting-lever 7 is now grasped and the said lever swung from left to right until its indicator or pointer 9 registers upon the dial 10, the number of minutes or even hours that it is 70 desired shall elapse before the device, so to speak, is "sprung" for cutting off or turning off the supply of gas or electric current or water, or whatever else the timing mechanism is designed to control. At 75 the beginning of the above described direct manual movement of the setting-lever 7 from left to right, its coupling-notch 59 is pulled away from the stem 56, whereby the supply-limiting lever 19 is released to 80 the action of its spring 54 and abruptly lifted with its stop-pin 18 which now engages with and rides upon the periphery of the timing-disk 16, the slot 17 thereof having previously been carried out of line with the path of the pin 18 by the slight rotation of the timing-disk 16 due to the initial movement of the setting-lever 7 from left to right as already described.

The manual swinging of the setting-arm 90 7 as described, from left to right turns the arbor 23 and proportionally winds the main spring 26. The ratchet wheel 27 turning with the arbor 23, causes the pawl 28 to "take a hitch", so to speak, on the spring 26 85 which it thus connects with the time-train which at once begins to run. As the time-train runs, the spring 26 unwinds and slowly turns the timing-disk 16 back to its zero-position and so brings the lower end of its 100 slot 17 into registration with the stop-pin 18. As soon as this takes place, the spring 54 asserts itself and raises the stop-pin 18 in the said slot 17. This takes place at the 105 termination of the time-limit at which the device was set when the lever was swung to wind the spring.

The main spring is always kept under some tension and would tend to keep the train running and so cause the pin 18 to 110 bind in the slot 17. To prevent this, a stop-pin 60 is mounted in the disk 16 in position to engage with a fixed portion of the movement just as the pin 18 enters the slot 17. As shown, the stop-pin 60 engages with a 115 nut 61 on the pillar 62, but any fixed part of the device will answer this purpose. By keeping the spring 26 normally under tension, the timing-dial is normally maintained in its zero position by being turned 120 until the stop-pin 60 engages with a fixed point of some sort.

As the timing-pin 18 snaps into the slot 17 under the action of the spring 54, the supply-limiting lever 19 is smartly lifted, carrying with it a vertically arranged operating-link 63 the upper end of which is connected with the said lever 19, while its lower end is pivotally connected with a slotted head 64 mounted on the shank 65 125

of a valve-operating lever 66 located between two arms 67, 67, cast integral with and depending from the valve-body 68. The pivot 69 on which the lever 66 swings is mounted in these arms. The said lever 66 engages with the projecting lower end of a valve-stem 70 the upper end of which carries a ball-valve 71 co-acting with a seat 72 in the valve-body or casing 68 which is located within the case 11 and fastened to the frame-plate 14. A valve-spring 73 encircling the lower end of the valve-stem 70 is provided for normally holding the valve 71 upon its seat 72. The upper coil of the spring 73 impinges against a washer 74 which in turn holds a packing 75 in place, while the lower coil of the spring 73 rests upon an adjusting nut 76 on the lower end of the valve-stem. The said valve-body 68 is chambered to form a horizontal gas-passage 77 to which gas is supplied by means of a short intermediate gas-pipe 78 permanently located within the lower portion of the case 11, and, as shown, having its outer end connected with the main gas-supply pipe 79. The horizontal gas-passage 77 intersects the lower end of a vertical gas-passage 80 terminating in the valve-seat 72 which is located at the lower end of a valve-chamber 81 capped with an ordinary plug 82 and intersected by a threaded nipple 83 receiving, as shown, a coupling-pipe 84 (Fig. 1) running into the base of the heater 2 and thus to the burner within the same. A small pilot-light nipple 85 is tapped into the valve-body 68 at a point below the valve 71 and in line with the gas-pipe 78 so as to receive a sufficient supply of gas therefrom to support a pilot-light. The nipple 85 receives a pilot light tube 86 (Fig. 1) leading into the base of the heater 2, and hence to a pilot-light burner which is not shown.

My improved timing-mechanism may be used on either side of the heater 2. As shown it is connected on the right hand side thereof. To connect it on the left hand side thereof, the supply pipe 79 will be shifted to the nipple 83, and the coupling-pipe 84 shifted to the intermediate pipe 78 forming a permanent feature of the mechanism and contained within the casing 11 thereof. When the mechanism is used on the left hand side of the heater 2, the pilot-light nipple 85 will be plugged and the pilot-light tube 86 connected to a pilot-light tube 87 permanently mounted in the case 11 above the pipe 78 aforesaid, projecting at one end through the case and at its opposite end intersecting the valve-chamber 81.

In the modified construction shown by Fig. 9 of the drawings, my improved device is adapted to control the flow of an electric current rather than the flow of gas. For this purpose, the lower end of the link

63 is connected with the blade member 88 of a "knife-blade" switch also comprising spring-fingers 89, a post 90, and terminal binding posts 91 and 92 respectively connected with the said spring-fingers 89 and post 90. Current is brought to the mechanism by a wire 93 attached to the binding-post 92 and leaves the mechanism through a wire 94 attached to the post 91, or the direction of the current may be reversed. It will be readily understood that when the operating-lever 19 is pulled down by its knob 58, the link 63 will descend and force the blade 88 between the fingers 89 and thus close the electric circuit which will be broken the instant the time-limit to which the device was set expires, by the lifting of the blade 88 through the medium of the link 63 and arm 19, due to the action of the spring 54.

The modification illustrated by Fig. 9, sufficiently indicates how my improved timing mechanism may be utilized, in other ways than by putting a time limit upon the supply of gas. The character of the mechanism operated by the link 63 will, of course, be varied in accordance with the character of the commodity being supplied. The notch 59 is used for convenience, but may be dispensed with in which case both hands will be required for the operation of the device.

I call particular attention to the fact that in my improved device the turning on of the gas or electric current or what not, is made a condition precedent to the setting of the timing-mechanism. Thus, the manually operable supply-limiting lever 19 must be drawn downward to entirely clear the timing-pin 18 from the slot 17 in the timing-disk 16 to release the same for being turned by the setting-lever 7. This construction insures the conservation of the gas or current or whatever else is measured by the timing-mechanism. If my invention is applied to measure the fuel gas supplied to a water-boiler for heating the water, the user will be insured the heating of the water and the cutting off of the gas at a predetermined time, since when he operates the supply-limiting lever 19 as a condition precedent to setting the timing-mechanism, the gas is automatically lighted by the pilot light, while the setting of the timing-mechanism immediately following the turning on of the gas, provides for automatically turning off the gas at a predetermined time.

I would further call attention to the fact that whereas the turning on of the gas is a condition precedent to the setting of the timing-mechanism, the setting of the timing-mechanism is a condition precedent to maintaining the gas-cock open, since after the timing-pin 18 has been cleared from the timing-slot 17, it will immediately be re-

entered into the slot by the action of the spring 54, unless while the lever 19 is pulled down, the setting-lever 7 is swung so as to move the slot 17 out of registration with the timing-pin 18 and bring the edge of the timing-disk 16 into position to be engaged by the pin 18 which then acts to hold the lever 19 against the tension of the spring 54, and thus hold the gas-cock open.

10 It will be seen from the foregoing that the manual operation of the supply-limiting lever 19 is a condition precedent to the setting of the timing-mechanism, and that the setting of the timing-mechanism is a condition precedent to holding the supply-limiting lever 19 in position to keep the gas turned on. This principle of operation would hold good for the measuring of an electric current.

15 20 I also call attention to the self-contained character of my improved apparatus, whereby the timing-mechanism, the device-to-be-timed, and the connection between the said mechanism and device are compactly located within one and the same case.

I claim:—

1. In a timing-mechanism, the combination with an arbor, a driving spring therefor, a timing-disk concentric with the arbor and rotated thereby, a setting-lever for turning the said arbor and disk, a supply-controlling lever manually operable for releasing the said disk to permit the same to be set by the setting-lever and automatically released by the said disk at a predetermined time, means connecting the said manually operable supply-controlling lever with the device to be timed, and means whereby the setting operation of the supply-controlling lever to release the disk must precede the setting operation of the setting lever.

2. The combination with a timing mechanism having an arbor, a driving spring therefor, and a timing-disk rotated by the said arbor and provided with a timing-slot; of a combined setting-and-winding lever for simultaneously turning said arbor and disk for setting the said mechanism and proportionately winding the said spring, a manually operable supply-controlling lever co-acting with the said disk and the slot thereof, means for connecting the said supply-controlling lever with the device to be timed, and means whereby the operation of the supply-controlling lever must precede the operation of the combined setting-and-winding lever for setting the mechanism.

3. In a timing-mechanism, the combination with a case, of an arbor located therein, a driving spring for the said arbor, a timing-disk located within the said case and mounted upon the arbor, a combined setting-and-winding lever connected with the arbor and located upon the outside of the said case, a manually operable supply-control-

ling lever located within the case but operable from the outside thereof, a device to be timed located within the case, means located within the case for connecting the said supply-controlling lever with the device to be timed, and means whereby the operation of the supply-controlling lever for the release of the disk must precede the operation of the combined winding-and-setting lever for setting the mechanism. 75

4. In a timing-mechanism, the combination with a case, of an arbor located therein, a driving-spring for the said arbor, a timing-disk mounted upon the said arbor and turning therewith, a dial located upon the outside of the case, a combined setting-and-winding lever located in front of the said dial and connected with the said arbor, a supply-controlling lever located within the said case, manually operable from the exterior thereof and co-acting with the said disk by means of which it is released at a pre-determined time, a device to be timed located within the case, means connecting the supply-controlling lever with the device to be timed, and means whereby the setting operation of the supply-controlling lever must precede the setting of the disk by the combined setting-and-winding lever. 80 85 90

5. In a timing device, the combination with an arbor, a driving spring therefor, a timing-disk mounted upon the said arbor and rotated thereby, a combined setting-and-winding lever mounted upon the said arbor, a manually operable supply-controlling lever co-acting directly with the said disk, a device to be timed, and connection between the said supply-controlling lever with the device to be timed, the said setting-and-supply-controlling levers being adapted 100 105 to be coupled together in setting the mechanism.

6. The combination with a case, of an arbor located therein, a driving spring therefor, a timing-disk mounted upon the arbor and rotated thereby, a combined setting-and-winding lever operable from the exterior of the case for turning the said arbor, a supply-controlling lever manually operable from the exterior of the case, a device to be timed, means connecting the said manually operable supply-controlling lever with the device to be timed, the said levers being notched to permit them to be coupled together, and means whereby the operation of the supply-controlling lever for the release of the disk must precede the operation of the combined winding-and-setting lever for setting the disk. 110 115 120

7. The combination with a timing mechanism having an arbor, a driving spring therefor, and a timing-disk rotated by the said arbor and furnished with a timing-slot, of means for setting the said mechanism and proportionately winding the spring thereof 125 130

- at one and the same operation, a manually operable supply-controlling lever co-acting with the said disk and the slot thereof, a device to be timed, means connecting the 5 said supply-controlling lever with the device to be timed, and means whereby the setting operation of the supply-controlling lever must precede the setting operation of the combined setting-and-winding means.
- 10 8. The combination with a case, of a timing mechanism located therein and having an arbor, a driving spring therefor, and a timing-disk mounted upon the arbor and rotating therewith, of a combined setting- 15 and-winding lever operable from the outside of the case and mounted upon a projecting end of the arbor, a manually operable sup-

ply-controlling lever located within the said case but operable from the outside thereof, a device to be timed, means located within 20 the case for connecting the supply-controlling lever with the device to be timed, and means whereby the setting operation of the supply-controlling lever must precede the setting operation of the combined-setting- 25 and-winding lever.

In testimony whereof, I have signed this specification in the presence of two subscribing witnesses.
